EVAPORATOR DOOR AND HINGE ASSEMBLY

Florence B. Anderson, Winnetka, Ill., assignor to Motor Products Corporation, Detroit, Mich., a corporation of New York

Application March 31, 1952, Serial No. 279,640

15 Claims. (Cl. 20—35)

This invention relates generally to refrigerators and refers more particularly to an improved evaporator compartment door and hinge assembly therefor.

One of the objects of this invention is to pivotally or hingedly support the evaporator compartment door on the liner of the refrigerator cabinet independently of the evaporator compartment. Hence the relation between the top of the evaporator compartment door and the adjacent wall of the refrigerator cabinet may be more closely controlled, and the danger of ice accumulation at the pivots or hinge mountings is less than in constructions where the door is mounted on the evaporator compartment.

Another object of this invention is to provide an evaporator compartment door comprising laterally spaced inner and outer panels molded from plastic or some equivalent thermal insulating material, and preferably having insulating material disposed in the space between said panels. Such a construction not only renders it possible to produce the door panels by inexpensive molding operations, but in addition, retards the formation of ice or frost on the door.

Another object of this invention is to provide a door normally urged to its closed position relative to the evaporator compartment by a torsional spring fixed to the door and having end portions actuated by the hinge pins or trunnions for the door. More particularly the end portions of the torsional spring extend into bores provided in the hinge pins or trunnions, and are provided with lateral projections engageable in open transversely extending slots in the inner ends of the trunnions. Thus the torsional door closing spring is tensioned upon swinging the evaporator door toward its open position and biases the door toward its closed position.

Another object of this invention is to provide the door with reinforcing members in the form of arms secured to opposite sides of the door within the space between the door panels, and journaled on the trunnions to pivotally support the door without unduly stressing the door panels.

Another object is to provide an evaporator door structure composed of relatively few parts capable of being readily manufactured, assembled and installed.

The foregoing as well as other objects will be made more apparent as this description proceeds, especially when considered in connection with the accompanying drawings, wherein:

Figure 1 is a fragmentary front elevational view of a refrigerator showing the door in its open position;

Figure 2 is an enlarged sectional view taken on the line 2—2 of Figure 1;

Figure 3 is a fragmentary side elevational view of the evaporator compartment showing the door in its open position;

Figure 4 is a fragmentary perspective view of the evaporator door and hinge assembly;

Figure 5 is a sectional view taken on the line 5—5 of Figure 2;

2

Figures 6 to 10 inclusive are respectively sectional views taken on the lines 6—6, 7—7, 8—8, 9—9, and 10—10 of Figure 5;

Figure 11 is a fragmentary perspective view taken on the line 11—11 of Figure 1; and

Figure 12 is a fragmentary perspective view taken on the line 12—12 of Figure 1.

In Figure 1 of the drawings there is illustrated the top portion of a domestic refrigerator having a conventional cabinet 15 provided with an opening 16 at the front and having a door 17 for closing the opening 16. Supported within the cabinet 15 adjacent the top of the latter is an evaporator compartment 18 having an opening at the front registering with the opening 16 in the cabinet and having a closure 20 for the opening at the front of said evaporator compartment. The evaporator compartment 18 is not shown in detail herein, but it will be noted from Figure 1 that this compartment extends substantially from one side wall to the other of the liner 21 of the refrigerator cabinet.

As shown in the figures, the closure 20 for the evaporator compartment 18 is in the form of a door having an outer panel 22 and an inner panel 23 spaced laterally from the outer panel to provide a space 24 of substantial width between the panels. To minimize accumulation of frost or ice on the closure or door 20, both panels 22 and 23 are preferably formed of a plastic or some equivalent material having thermal insulating characteristics, and a heat insulating material 25 is provided within the space 24 between said panels. The design of the door panels 22 and 23 is such as to permit them to be formed by a relatively simple molding process, and hence each panel is of one piece construction.

As shown in Figure 8, the outer panel 22 has a flange 26 turned laterally inwardly from the bottom edge thereof, and the inner panel 23 has a flange 27 turned laterally inwardly from the bottom edge thereof. Preferably, the flange 27 overlies the flange 26 and is provided at longitudinally spaced points thereof with thickened portions 28 for receiving fastener elements 29 which extend upwardly through the flange 26. As shown in Figures 5 and 9, the flange 26 may also be recessed to receive the heads of the fastener elements 29 so that the latter are substantially concealed from view.

As shown in Figure 6 of the drawings, flanges 30 are turned laterally inwardly from opposite side edges of the front panel 22, and extend into abutting engagement with the adjacent edge portions of the inner panel 23. The side flanges 30 form a continuation of the bottom flange 26 and provide the opposite side walls of the door 20. Suitable reinforcing ribs 31 project outwardly from the inner panel 23 and respectively extend along opposite side edges of the inner panel. Referring again to Figure 6 of the drawings, it will be noted that the ribs 31 are spaced laterally inwardly from the adjacent flanges 30, and are attached to the flanges 30 by fastener elements 32 having head portions positioned in countersunk recesses formed in the flanges 30. Additional reinforcing ribs 33 (Figure 5) are also formed on the inner panel 23, and these ribs are arranged to effectively reinforce the door 20.

The door is further reinforced by metal arms 34 respectively positioned within the spaces provided between the side flanges 30 on the outer panel 22 and the ribs 31 on the inner panel 23. The arms 34 are secured in place by the fastener elements 32, and the lower ends 35 are offset laterally outwardly in the manner shown in Figure 5 of the drawings. The adjacent or lower ends of the flanges 30 are slotted or cut away as at 36 to provide the clearance required for the offset portions 35 at the lower ends of the reinforcing arms 34.

Referring now to Figures 11 and 12 of the drawings,

it will be noted that the inner panel 23 has an outwardly projecting rib 37 spaced downwardly from the top edge to provide a seat, and also has an outwardly extending rib 38 spaced downwardly from the rib 37. The outer edge portion of the rib 38 is turned upwardly to form with the inner surface of the panel 23 an upwardly opening channel 39. The top portion of the outer panel 22 is fashioned to provide an inwardly opening channel-shaped section 40 having the inner edge of the top flange seated on the rib 37 and abutting the inner panel 23. The bottom leg 42 of the channel-shaped section 40 extends inwardly beyond the outer panel 22 and is turned downwardly to form a hook 43. The hook 43 is engageable in the upwardly opening channel 39 on the inner panel, and cooperates with the seat or rib 37 to hold the top edge portions of the door panels in assembled relationship.

As shown particularly in Figures 11 and 12 of the drawings, the bottom leg portion 42 of the channel-shaped section 40 also projects outwardly beyond the top edge of the outer panel 22, and the latter is embossed in an inward direction intermediate opposite side edges of the door to provide a recess 44 directly below the channel section 40. The arrangement is such as to provide a convenient handle 45 for manipulating the door 20 of the evaporator compartment 18. It is pointed out that the bottom leg portion 42 of the channel-shaped section 40 is omitted in the region of the embossed portion 44 to facilitate gripping the door 20 adjacent the top of the latter. It will also be noted that the upturned flange on the rib 38 is also omitted opposite the embossed portion 44 and that an additional reinforcing rib 47 is provided on the inner panel 23 between the ribs 37 and 38 in the order to further strengthen the door in the region of the handle 45.

The evaporator door 20 is hingedly supported at its bottom edge to enable outward swinging movement of the door relative to the evaporator compartment 18. In the present instance a pair of plates 48 are respectively secured to opposite sides of the liner 21 for the refrigerator cabinet, and pivot pins or trunnions 49 are respectively secured to the plates 48. The plates 48 are secured in place by fastener elements 50, and the trunnions 49 project inwardly from opposite side walls of the liner 21 in axial alignment. The trunnions are tubular in cross section, and are fashioned with a transversely extending slot 51 at the inner or free ends thereof. As shown in Figure 2 of the drawings, the trunnions 49 respectively project through openings 52 formed in the offset portions 35 of the reinforcing arms 34. Thus the arms 34 are respectively journaled on the trunnions 49 to enable swinging movement of the door 20 about the aligned axes of the trunnions 49. The extent of opening movement of the door is limited by the engagement of projections 53 on the lower ends of the arms 34 with stops 54 respectively formed on the plates 48. The arrangement is such that when the evaporator door 20 is in its fully opened position, the projections 53 respectively engage the undersides of the stops 54 on the plates 48, and prevent further movement of the evaporator door 20 in a door opening direction.

The evaporator door 20 is normally urged to its closed position with respect to the opening 19 at the front of the evaporator compartment by a torsional spring 55 located within the space 24 between the inner and outer door panels. The spring 55 has an inverted substantially U-shaped portion 56 positioned intermediate the ends of the door, and is secured to the inner door panel 23. Referring again to Figure 5 of the drawings, it will be noted that the top 57 of the U-shaped portion 56 abuts a centrally disposed reinforcing rib 58 on the inner door panel, and the legs of the inverted U-shaped portion respectively extend between projections 59 on the inner door panel 23. The lower ends of the leg portions of the spring 55 are turned laterally outwardly to form

straight sections 60 positioned in substantial alignment with the journals 49. The straight sections 60 extend along the bottom flange 26 of the door 20, and the vertical reinforcing ribs 33 on the inner panel are slotted as at 61 to provide clearance for the straight sections 60.

If desired the straight sections 60 of the spring 55 may be clamped to the inner door panel 23 at opposite sides of the U-shaped portion 56 by clamps 61'. As shown in Figure 8 of the drawings, each clamp 61' comprises laterally spaced projections 62 extending outwardly from the inner panel 23, and a spring washer 63 frictionally secured to the projections 62. The spring washers 63 respectively engage the straight sections 60 of the spring 55 at the outer sides thereof and hold the same in position.

The extremities of the straight sections 60 project axially into the trunnions 49, and are reversely bent as at 64. The reversely bent portions 64 actually provide lateral projections on the extremities of the straight spring sections 60, and these projections assume positions within the slots 51 in the trunnions in order to prevent relative rotation of the trunnions and straight sections 60 of the spring. In assembly the trunnions 49 are respectively assembled on the extremities of the straight spring sections 60, and the plates 48 are subsequently secured by the fastener elements 50 to the liner 21 of the refrigerator cabinet. In accomplishing this result the spring 55 is tensioned to some extent so that the door 20 is normally held in its closed position relative to the open side 19 of the evaporator compartment. Of course opening of the door 20 further tensions the spring 55, and closing movement of the door is facilitated by the spring 55.

Thus, from the foregoing, it will be appreciated that the evaporator compartment door 20 is hingedly supported on the liner 21 of the refrigerator cabinet 15 independently of the evaporator compartment 18. This arrangement is advantageous in that it not only facilitates obtaining the proper relationship between the top edge of the evaporator door and the adjacent wall of the refrigerator cabinet, but in addition, locates the pivots or trunnions in positions where they are not so susceptible to the accumulation of frost and ice. It will also be noted that the door panels 22 and 23 are formed of a plastic material, and are reinforced by the members 34 which also serve as a support for the door on the trunnions 49. Thus the reinforcing members 34 carry the major portion of the weight of the door and thereby prevent breaking or cracking of the door panels during use. It will further be noted that the construction of the door is such as to enable the same to be readily and inexpensively manufactured.

What I claim as my invention is:

1. In a refrigerator cabinet having a liner an evaporator compartment within said cabinet: a door for said compartment, carried by said liner and having spaced inner and outer panels, an inwardly opening substantially channel-shaped bordering portion extending along the top of the outer panel and having vertically spaced top and bottom flanges, the bottom flange extending inwardly beyond the outer panel, a flange projecting downwardly from the inner edge of the bottom flange forming a hook, a seat on the inner panel adjacent the top edge thereof and engageable with the top flange of the bordering portion, and means on the inner panel forming an upwardly opening recess for removably receiving said hook.

2. The construction defined in claim 1 wherein the outer panel is embossed inwardly intermediate opposite side edges and directly below the bordering portion to form with the latter a handle.

3. A hollow insulating door construction comprising front and rear rectangular panels, abutting inwardly extending flanges along all four corresponding edges of said panels, interlocking hook constructions on said panels in the space defined by said flanges and retained in hooked interlocked relation by said flanges, and fastening elements securing said flanges to each other.

4. A hollow insulating door construction comprising front and rear rectangular panels having abutting inwardly extending flanges along all four sides thereof and interlocking hook constructions in the space defined by said flanges, said flanges shaped to prevent separation between said hook constructions so long as said flanges are engaged, and fastening elements extending through the abutting flanges at the side of said door opposite to said hook constructions.

5. A hollow door construction having mounting strips along the ends thereof within said door, said door having openings adjacent corresponding ends of said strips, said strips having apertured mounting portions extending outwardly through said openings, aligned mounting pins extending through the openings in said mounting portions and said door, and a balance spring having its ends fixedly secured to said pins and including a central portion bent laterally from the axis of said pins to exert turning force on said door about the axis of said pins.

6. A hollow door having aligned openings in opposite edges adjacent a third edge of said door, mounting pins extending through said openings, said pins having transversely extending slots at their inner ends and recesses inwardly of the bottoms of said slots, a torsion spring in said door having a central portion looped to engage inner door surfaces remote from the axis of said pins, and aligned end portions extending axially of said pins, the ends of said spring being seated in said recesses, and the end portions of said springs including lateral extensions in said slots to prevent rotation of the ends of said spring.

7. Structure as defined in claim 6, said lateral extensions being formed by laterally bent portions of said spring.

8. A door comprising a front and a rear panel; said rear panel having a forwardly extending top flange spaced slightly below its upper edge, a forwardly extending hooked flange adjacent its upper edge but below said top flange and terminating at its forward edge in an upwardly projecting hook, and a forwardly extending bottom flange spaced slightly above its bottom edge, said front panel having a rearwardly extending top edge portion terminating in an edge seated on the top of the said top flange of said rear panel, a rearwardly extending flange below its top edge having a depending hook along its rear edge engaged over the hook on the hooked flange of said rear panel, and a rearwardly extending bottom flange engaging below the bottom flange of said rear panel; and fastening means extending through said bottom flanges and effective to prevent separation between said panels.

9. Structure as defined in claim 8, said front panel having a recessed portion adjacent its top edge, the upper surface of said recess having an opening therethrough providing a finger hold for swinging said door forwardly.

10. A hollow door comprising a rear panel having a substantially continuous forwardly projecting flange extending around its periphery and spaced inwardly from the edges of said panel and having an upwardly open, forwardly projecting channel means extending across the panel adjacent to but below the top portion of the flange thereof, a front panel having a substantially continuous rearwardly projecting peripheral flange engaging the front surface of said rear panel outwardly of the forwardly pro-

jecting flange thereof, said front panel having rearwardly projecting hook means adjacent to but below the top portion of the flange thereon, said hook means including downwardly projecting parts received in said channel means.

11. A door as defined in claim 10 in which the top and bottom portions of the rearwardly projecting peripheral flange on said front panel respectively engage the upper surface of the top portion and the lower surface of the bottom portion of the forwardly projecting flange on said rear panel.

12. A hollow door and mounting structure therefor comprising a rear panel having a forwardly extending horizontal top flange spaced slightly below its top edge to form a seat, a forwardly extending upwardly open channel immediately below said top flange, and a forwardly extending horizontal bottom flange spaced slightly above its bottom edge; a front panel having a rearwardly extending hook portion adjacent its upper edge received in said channel, rearwardly extending top and bottom flanges respectively received on said seat and engaged beneath the bottom flange of said rear panel; and fastening means connecting the bottom flanges of both of said panels.

13. A hollow door and mounting structure therefor comprising a rear panel having a forwardly extending upwardly open channel extending longitudinally of its upper edge, forwardly extending vertical side flanges spaced inwardly from its ends, and a forwardly extending bottom flange spaced upwardly from its bottom edge; a front panel having at its rear side and adjacent its upper edge a downwardly extending hook portion received in said channel, rearwardly extending vertical side flanges at its ends overlying the side flanges on said rear panel, and a rearwardly extending bottom flange at its bottom edge engaged beneath the bottom flange of said rear panel; and fastening means connecting the bottom flanges of said panels.

14. Structure as defined in claim 13, said vertical flanges at each end of said door being spaced apart, mounting strips received between said last mentioned flanges, the lower portions of the vertical flanges on said front panel terminating above the bottom of said door to form openings, the lower portions of said mounting strips extending outwardly through said openings and having pin receiving openings.

15. Structure as defined in claim 14, and pivot pins extending through the openings in said strips and the openings in said door.
